UNITED STATES PATENT OFFICE.

EARL RANSOM PERKINS, OF CLEVELAND, OHIO.

AUTOMATIC GAS-PRESSURE ALARM.

1,009,338.

Specification of Letters Patent. Patented Nov. 21, 1911.

Application filed January 7, 1908, Serial No. 409,709. Renewed March 14, 1910. Serial No. 549,358.

To all whom it may concern:

Be it known that I, EARL R. PERKINS, a citizen of the United States, residing at Cleveland, in the county of Cuyahoga and 5 State of Ohio, have invented a new and useful Improvement in Automatic Gas-Pressure Alarms, of which the following is a specification.

This invention relates to alarms especially 10 adapted to be used on gas pipes leading to furnaces, the object being to provide an alarm which will be sounded when the flow of gas through the pipe is stopped or decreased to such an extent that the back pressure 15 sure in the furnace might blow the gas out.

With this object in view, the invention consists in the novel features of construction, combination and arrangement of parts hereinafter fully described and pointed out 20 in the claims.

In the drawing forming a part of this specification:—Figure 1 is a side elevational view of my improved alarm. Fig. 2 is a longitudinal sectional view of the same, the 25 battery, bell and switch being omitted. Fig. 3 is a sectional view. Fig. 4 is a longitudinal sectional view through the alarm showing the circuit closed.

In the drawing A indicates a casing 30 formed of two sections A', A² connected together by screws and having a rubber gasket arranged between the same, so as to form an air-tight joint. The sections being provided with oppositely disposed threaded 35 bores in which are secured the threaded ends of the supply-pipe B and the discharge pipe C, the supply-pipe B extending into the casing and having a rubber sleeve D secured over its end which is cut off 40 obliquely and has a brass washer E secured over its end, the face of which is roughened, and is connected to the end of a line-wire F which passes through a rubber plug arranged in a bore formed in the casing and 45 is connected to a bell G for sounding an alarm as will be hereinafter fully described. The wire being provided with a switch F', so that the circuit can be broken thereby preventing the bell from ringing after the 50 gas has been cut off.

The section A² of the casing is provided with oppositely disposed openings in its sides, in which are arranged rubber sleeves H through which extend binding posts I, 55 to which is connected a line-wire J leading from a battery K which is connected to the

bell G by a wire K'. The inner ends of the binding post I are provided with needle-bearings in which is pivotally mounted a pointed end of a shaft L which is provided 60 with an arm L' carrying a brass-gauze frame M which is provided with a central opening and is covered on its outer face by a thin sheet of paraffin coated paper N so as to prevent the gas from passing 65 through the gauze and it will be seen that this frame will be normally held out of engagement with the brass-washer E by the pressure of the gas and when the pressure is reduced, the frame will drop by gravity and 70 complete the circuit, so as to sound the alarm and prevent any danger of an explosion if the burner should go out and the supply of gas be returned to its normal position.

From the foregoing description it will be seen that I have provided an arm with very novel means for closing an opened circuit when the flow of gas is decreased.

Having thus fully described my invention, 80 what I claim as new and desire to secure by Letters Patent is:—

1. In a device of the kind described, the combination with a casing provided with inlet and outlet pipes through which fluid 85 is adapted to flow, of a washer forming a contact carried by the inlet pipe, a pivoted arm mounted in the casing carrying a wire gauze frame forming a contact normally in contact with the washer, an electrical 90 alarm circuit having terminals connected respectively to said contacts, and a non-porous, non-conducting cover for said gauze.

2. The combination with a casing provided with an inlet and an outlet pipe 95 through which fluid is adapted to be passed, of a rubber tube secured over the inlet pipe, a contact carried by the rubber tube, a pivoted contact mounted in said casing and normally in contact with the first mentioned 100 contact, and adapted to be held away from said contact by the pressure of the fluid, and an electrical alarm circuit having its terminals connected, respectively, with said contacts.

3. In a device of the kind described, the combination with a casing provided with an inlet and an outlet pipe, of a sleeve arranged over the end of the inlet pipe within said casing, a contact member secured over the 110 end of said sleeve, binding posts secured in the side walls of said casing over said sleeve,

said binding posts being provided with needle-bearings, a shaft mounted in said bearing provided with an arm, a gauze frame carried by the arm, a paper covering on the outer face of the gauze frame, and an electrical alarm circuit having one terminal connected to the binding posts and the other terminal connected to the contact member,

respectively, whereby an alarm will be sounded when said gauze-frame engages 10 said contact member.

EARL RANSOM PERKINS.
